FUEL CONTROL APPARATUS**Joseph L. Devere, Milwaukee, Wis., assignor to Baso Inc., a corporation of Wisconsin****Application February 7, 1955, Serial No. 486,395****8 Claims. (Cl. 137—66)**

This invention relates to improvements in fuel control apparatus.

It is a well known practice in the art of controlling the flow of fuel to fluid fuel burners to provide safety shut-off devices effective to shut off the supply of fuel to the main burner of the apparatus and also, if desired, to the pilot burner therefor upon occurrence of a predetermined condition. Such safety shut-off devices may have electromagnetic control means powered from a thermoelectric generator subject to the heat of the pilot burner flame to effect 100 percent shut-off of the fuel in the event of pilot failure. Further, it is well known in the art to provide means for permitting fuel flow to the pilot burner while interrupting fuel flow to the main burner during a resetting operation so that the thermoelectric generator is heated by the pilot burner flame prior to fuel flow to the main burner. The reset means is usually of the manual type wherein a reset plunger or stem is reciprocatably depressed to afford fuel flow to the pilot burner. It is therefore a general object of the present invention to provide a pilot fuel valve having rotary actuating means operable to open said pilot valve in response to reciprocatory resetting movement of a reset stem, to maintain the same in open position during ignition of a pilot burner and to close the same upon release of the safety shut-off device.

Another object is to provide a fuel control device of the class described wherein the main fuel valve is held closed during resetting of the electromagnetic safety shut-off mechanism to thus provide flow interruption.

Another object of the present invention is to provide an improved control device of the character described wherein fuel flows to the pilot burner during a resetting operation ignition of which energizes the electromagnetic safety shut-off mechanism and magnetically latches the armature thereof to the electromagnet, release of the reset mechanism while the armature is thus latched effecting opening movement of the main fuel valve and retention of the pilot fuel valve in its open position.

Another object of the invention is to provide an improved control device of the character described wherein the electromagnetic safety shut-off mechanism includes an electromagnet and an armature which are juxtaposed in open valve position and in reset position, and which are spaced apart a substantial distance in released or closed position, there being cam means connected to said electromagnet and armature and positioned for actuation of the pilot fuel valve to hold the latter open when the armature and electromagnet are juxtaposed, said cam means being operable to hold the pilot fuel valve open continuously during movement of the electromagnet and armature from reset to open valve position and to permit closure of said pilot fuel valve with the safety shut-off valve upon predetermined separation of said electromagnet and armature.

Another object of the invention is to provide an improved fuel control device of the character described having a pilot fuel passage and a main fuel passage which

2

are separated from each other, the fuel flow through both of said passages being under the control of the safety shut-off means, whereby the main fuel passage may be connected to one fuel source, for example through a 5 thermostatically controlled valve, and the pilot fuel passage may be connected to another fuel source or to the same source at a point upstream from said thermostatically controlled valve, the flow of pilot fuel thus being independent of the operation of the thermostatically controlled valve. The improved device, therefore, permits the insertion of the thermostatically controlled valve into the main fuel line upstream from said device, while at the same time providing safety shut-off of both main and pilot fuel.

Another object is to provide a device of the class described wherein flow interruption of main fuel is provided during resetting regardless of whether or not the fuel passages to the main and pilot burners are separate and independent.

Another object of the present invention is to provide an improved fuel control device of the class described which is so constructed that a condition responsive valve may be employed upstream or downstream of the main fuel flow control valve to render fuel flow to the main burner subject to predetermined conditions while retaining safety shut-off control over the main and pilot burner fuel in the improved control device.

Another object is to provide an independent pilot fuel valve having rotary actuating means whereby the use of 30 O rings in providing a gas-tight seal around such rotary actuating means is appreciably more efficient than the use thereof with actuating means of the reciprocatory type.

Another object is to provide rotary pilot valve actuating means and connection between the same and reciprocatably operable reset means so as to reduce the occurrence of objectionable bending forces which are prevalent in systems wherein reciprocating reset movement is transmitted to a reciprocatably operable valve 40 member.

Another object is the provision of a control device having an independent pilot fuel valve having a rotary operating mechanism whereby the valve and operating mechanism parts are less susceptible of excessive wear and greater fuel flow capacity is provided than with pilot valve of the reciprocating type.

A more specific object is the provision in a control device of the aforementioned character of connecting means between the reset stem and the pilot and main valves 50 whereby bending or twisting forces applied to the reset stem will not be transmitted to either of the valves to cause faulty operation.

Another object is the provision of a control device of the class described which is simple in construction, inexpensive to manufacture and positive in operation.

The novel features which I consider characteristic of my invention are set forth with particularity in the appended claims. The device itself, however, both as to its organization and mode of operation, together with additional objects and advantages thereof, will best be understood from the following description of a specific embodiment when read in connection with the accompanying drawings, in which:

Figure 1 is a vertical sectional view of a fuel flow control device embodying the present invention and schematically shown connected to main and pilot burners;

Figure 2 is an elevational view of the control device of Figure 1, a portion of said device being broken away to expose the pilot fuel control valve in its flow-preventing position;

Figure 3 is a fragmentary view showing the electromagnetic safety shut-off mechanism of the improved con-

trol device in reset position and showing the operative coaction between the pilot valve actuating means and said mechanism; and

Figure 4 is a fragmentary view similar to Figure 3 showing the safety shut-off mechanism in retracted or open valve position and showing the operative coaction between the pilot valve actuating means and the main fuel control valve.

Like reference characters indicate corresponding parts throughout the several views of the drawings.

Referring to Figure 1 of the drawings, the numeral 10 designates a first valve body portion having a main fuel inlet 12 and a main fuel outlet 14. A main fuel passage 16 affords communication between the inlet 12 and outlet 14. Contiguous sections of fluid fuel supply pipe 18 may be connected to the inlet 12 and outlet 14, and the section connected to outlet 14 may be connected to a main fluid fuel burner 20 having a mixing chamber 20a.

Numer 22 designates a second valve body portion secured to the valve body portion 10 in any well known manner with a sealing gasket 98 disposed therebetween. The body portion 22 has a pilot fuel inlet 24 and a pilot fuel outlet 26 connected by a pilot fuel passage 28. Contiguous sections of pilot fuel supply pipe 30 are connected to the pilot inlet 24 and pilot outlet 26, and the section connected to said outlet 26 may be connected to a pilot burner 32 juxtaposed with respect to main burner 20.

The second valve body portion 22 is formed with a cavity 36 within which is disposed an electromagnetic safety shut-off or hood assembly 37 comprising an enclosure 38 and having a valve stem 42 extending from one end thereof. A main fuel flow control member or valve 40 is attached to valve stem 42 and is disposed for cooperation with a valve seat 34 within valve body portion 10 for control of communication between inlet 12 and outlet 14 and hence fluid fuel flow to main burner 20. I prefer to employ pivotal mounting means for securement of said valve member 40 to valve stem 42 to permit of relative movement therebetween for purposes of insuring firm seating engagement between valve 40 and valve seat 34.

Secured within enclosure 38 is a substantially U-shaped core member 44 formed with pole faces 44a and having an electromagnet winding 45 wound about the leg portions thereof. Fixed to said valve stem 42 within said enclosure 38 is an armature member 46 for cooperation with core member 44. The core member 44 and armature member 46 are magnetically permeable first and second movable members, and the winding 45 when energized comprises coupling means for retaining said members in attractive position when moved thereto.

Disposed on one end of said hood assembly enclosure 38, is a spring retainer 48 formed with a through opening to slidably permit valve stem 42 to move relative thereto. Positioned between valve member 40 and spring retainer 48 is a compression spring 50 for biasing the valve member 40 to its flow-preventing position and the armature 46 towards its separated or released position. Disposed between body portion 10 and the spring retainer 48 is a compression spring 54 for biasing the enclosure 38, and thereby the electromagnet core 44 and winding 45, toward their initial or normal retracted position shown in Figures 1 and 4.

The second valve body portion 22 is further formed with an opening 55 within which is insulatedly mounted an electrical contact member 56. One end of the electromagnet winding 45 is connected in circuit with said contact 56 for example by means of a flexible lead, and the other end of winding 45 is grounded to the second valve body portion 22 through a similar flexible lead. The opening 55 in body portion 22 is counterbored and formed with fastening means 57 such as threads for receipt of an electrical coupling member (not shown).

A thermoelectric generator or thermocouple 58 formed of a pair of dissimilar metals 59 and 60 and having a hot junction 58a and a pair of cold junctions 58b is disposed

adjacent the pilot burner 32 in heat receiving relation therewith. The thermocouple 58 is electrically secured to one end of a pair of conductors 62 while the other end of said pair of conductors is connected to the aforementioned coupling member to provide electrical continuity from thermoelectric generator 58 to electromagnet winding 45. I prefer that the conductors 62 take the form of a coaxial type thermocouple lead.

A reset stem 64 is slidably positioned within an opening formed in body portion 22 for engagement with an end wall of enclosure 38. Said stem 64 has its inner end extending through and spun over against a washer 65 whereby said stem is prevented from being removed from body portion 22. The other end of the stem 64 is formed with a manually engageable button 66. I prefer to employ an O-ring 68 between reset stem 64 and valve body portion 22 to prevent passage of fluid fuel therebetween.

Attached to enclosure 38, as by means of threaded extended portion 70 and securing nut 72, is first connecting means in the form of an L-shaped cam or connection member 74 which is movable with said enclosure and electromagnet core member 44 during a resetting operation. The cam member 74 has a portion 74a (Figures 3 and 4) extending parallel to the axis of movement of said enclosure 38. Fixedly secured to the valve member 40 is second connecting means in the form of an L-shaped cam or connection member 76 having a portion 76a extending parallel to extent 74a of cam member 74 but spaced laterally therefrom as shown in Figures 3 and 4.

The second valve body portion 22 is formed with a valve seat 78 as shown in Figures 1 and 2 and schematically depicted in Figures 3 and 4. Control means in the form of a valve member 80 formed of rubber or other resilient material cooperates with the valve seat 78 and is movable between first and second flow controlling positions with respect to the valve seat 78 for control of communication between pilot fuel inlet 24 and pilot fuel outlet 26 and hence fuel flow to pilot burner 32. Valve member 80 is formed with a resilient valve stem 82 having a cylindrical main portion 82a and an enlarged end portion 82b for cooperation with actuating means for said valve member 80. I prefer to have valve member 80 and valve stem 82 molded as a unitary structure to facilitate manufacture thereof and to eliminate need for fastening means therebetween. The valve actuating means comprises an operating lever 84 having one of its ends formed with an aperture to be forcibly slipped over enlarged end portion 82b during assembly and for loosely fitting around main portion 82a of stem 82. The other end of operating lever 84 is secured to an operating shaft 86 which is rotatably mounted in valve body portion 22. The inner end of the operating shaft 86 is formed with diametrically oppositely projecting ears 88, said ears each being positioned in the path of travel of a separate one of the cam or connecting members 74 and 76, as will hereinafter more fully appear.

The operating shaft 86 is rotatably biased in a valve closing direction by means of a torsion spring 90 positioned as shown in Figures 1 and 2. I prefer to employ an O-ring between shaft 86 and valve body portion 22 to prevent passage of fluid fuel therebetween. A cover 92 having a protruding central portion is fixedly mounted on valve body portion 22 by means of screws 94, and I prefer to employ a gasket 96 between said cover and said body portion to hermetically seal the actuating means for valve member 80 while affording easy access thereto for repair or other purposes.

The control device disclosed in the drawings operates as follows:

With valves 40 and 80 in their flow-preventing or first flow controlling positions (Figure 1) whereby fuel is not permitted to flow to either main burner 20 or pilot burner 32, hood assembly 37 is in its initial or retracted position. In order to effect ignition of pilot burner 32, it is

first necessary to actuate reset stem 64 by depressing reset button 66. The resulting resetting movement of stem 64 moves enclosure 38 in a direction to cause magnet core 44 to be moved from its initial to its attracted position with respect to armature 46. Such movement of enclosure 38 causes the end surface of portion 74a of cam or connection member 74 to engage one of the ears 88 on operating shaft 86 (as shown in Figure 3), whereby said shaft is caused to be rotated against the bias of the torsion spring 90 and in a direction to move pilot valve 80 to its flow-permitting or second flow controlling position. During depression of reset stem 64, the aforementioned resulting engagement of core member 44 with armature 46 causes the depressing force on reset button 66 to be transmitted to valve member 40 to thereby maintain the latter in its flow-preventing position, thus affording what is commonly referred to in the gas control art as flow interruption of fuel supply to the main burner 20.

With pilot valve 80 in its flow-permitting position, fluid fuel is permitted to flow to pilot burner 32. The fuel emitted from pilot burner 32 may be ignited in any desired manner.

Ignition of said pilot burner 32 effects heating of hot junction 58a of the generator 58, causing said generator to supply thermoelectric current for energization of the electromagnet winding 45 and the flux generated thereby magnetically latches or couples the core 44 and armature 46 with sufficient force to overcome the bias of spring 50. On release of the reset button 66 compression spring 54 returns the enclosure 38 and magnet core 44 to their initial or retracted positions and simultaneously moves valve member 40 to its flow-permitting position. If the force on reset button 66 should be released at any moment prior to attainment of the aforementioned magnetic latching, the enclosure 38 is returned to its retracted position by spring 54 without moving valve member 40 to its flow-permitting position and at the same time permitting the pilot valve member 80 to return to its flow-preventing position under the bias of torsion spring 90. Pilot valve closure is due to removal of extent 74a of cam or connection member 74 from contact with its respective ear 88 on operating shaft 86.

Upon movement of valve member 40 to its flow-permitting position, however, extent 76a of cam or connection member 76 is caused to engage the other ear 88 on shaft 86, as shown in Figure 4, to hold the pilot valve open as long as the main valve stays open. Thus, disengagement of the first ear 88 from extent 74a does not effect return of valve member 80 to its flow-preventing position when the main valve is open. With movement of the valve member 40 to its flow-permitting position, fuel is, of course, permitted to flow to main burner 20 through conduit 18.

If, for any reason, the flame of pilot burner 32 should be extinguished, the hot junction 58a of thermoelectric generator 58 will be cooled by the surrounding atmosphere thus deenergizing electromagnet winding 45 to a point where the magnetic attraction between core member 44 and armature 46 is insufficient to overcome the force of spring 50, whereupon the force of said spring moves valve member 40 to its flow-preventing position to interrupt fuel flow to main burner 20. Such movement of valve member 40 also effects disengagement of the extent 76a of cam or connection member 76 from the coating ear 88 on shaft 86 to thereby permit torsion spring 90 to return pilot valve 80 to its flow-preventing position terminating fuel flow to pilot burner 32.

It is thus seen that applicant has devised a structure wherein reciprocal resetting movement of the electromagnetic safety shut-off mechanism is operable to effect rotation of a rotatably operable independent pilot valve actuator, said structure providing flow interruption for pilot burner ignition and also providing 100 percent

safety shut-off of the fuel in the event of pilot burner failure.

Although I have shown and described certain specific embodiments of my invention, I am fully aware that many modifications thereof are possible. My invention, therefore, is not to be restricted except insofar as is necessitated by the prior art and by the spirit of the appended claims.

I claim:

1. In a control device, a first magnet member biased to a first position, a second armature member biased away from said first member to a first position and movable against said bias to a second position, said first member being movable against its bias to a second position engaging said second member, a shaft rotatable between first and second positions, a control member operatively associated with said shaft and movable between first and second controlling positions by rotation of said shaft between its first and second positions, cooperating abutment means on said first member and said shaft operable to rotate said shaft to its second position and to move said control member to its said second position on movement of said first member to its said second position, abutment means on said second member cooperating with the abutment means on said shaft and operable to retain said shaft and control member in their said second positions on movement of said second member to its said second position, and means coupling said first and second members when said first member is moved against its bias to its second position in engagement with said second member, the bias of said first member being operable, on release of said first member, to return the latter to its first position and move the coupled second member therewith to its said second position.
2. In a control device, a first member biased to a first position, a second member biased away from said first member to a first position and movable against said bias to a second position, said first member being movable against its bias to a second position engaging said second member, a shaft rotatable between first and second positions, a control member operatively associated with said shaft and movable between first and second controlling positions by rotation of said shaft between its first and second positions, cooperating abutment means on said first member and said shaft operable to rotate said shaft and to move said control member to its said second position on movement of said first member to its said second position, abutment means on said second member cooperating with the abutment means on said shaft and operable to retain said shaft and control member in their said second positions on movement of said second member to its said second position, and means coupling said first and second members when said first member is moved against its bias to its second position in engagement with said second member, the bias of said first member being operable, on release of said first member, to return the latter to its first position and move the coupled second member therewith to its said second position.
3. In a control device, a first member biased to a first position, a second member biased away from said first member to a first position and movable against said bias to a second position, a fluid flow control member on said second member being in flow-preventing position when said second member is in its first position and in flow-permitting position when said second member is in its second position, said first member being movable against its bias to a second position engaging said second member, a shaft rotatable between first and second positions, a control member operatively associated with said shaft and movable between first and second controlling positions by rotation of said shaft between its first and second positions, cooperating abutment means on said

first member and said shaft operable to rotate said shaft and to dispose said control member in its second position on movement of said first member to its second position, such movement of said first member to its second position maintaining said fluid flow control member in its flow-preventing position, abutment means on said second member cooperating with the abutment means on said shaft and operable to retain said shaft and said control member in their said second positions on movement of said second member to its said second position, such movement of said second member to its second position moving said fluid flow control member from its flow-preventing position to its flow-permitting position, and means coupling said first and second members when said first member is moved against its bias to its second position in engagement with said second member, whereby the bias of said first member, on release thereof effects return of the latter to its first position and movement of the coupled second member therewith to its second position to thus effect said retention of said control member in its second position and said movement of said fluid flow control member to its flow-permitting position.

4. In a control device, a first member biased to a first position, a second member biased away from said first member to a first position and movable against said bias to a second position, a fluid flow control member on said second member being in flow-preventing position when said second member is in its first position and in flow-permitting position when said second member is in its second position, said first member being movable against its bias to a second position engaging said second member, a shaft rotatable between first and second positions, a control member operatively associated with said shaft and movable between first and second controlling positions by rotation of said shaft between its first and second positions, cooperating abutment means on said first member and said shaft operable to rotate said shaft and to dispose said control member in its second position on movement of said first member to its second position, such movement of said first member to its second position maintaining said fluid flow control member in its flow-preventing position, abutment means on said second member cooperating with the abutment means on said shaft and operable to retain said shaft and said control member in their said second positions on movement of said second member to its said second position, such movement of said second member to its second position moving said fluid flow control member from its flow-preventing position to its flow-permitting position, and condition responsive coupling means for said first and second members operable during existence of a given condition when said first member is moved against its bias to its second position in engagement with said second member to couple said first and second members, whereby the bias of said first member, on release of said first member when coupled to said second member effects return of said first member to its first position and movement of the coupled second member therewith to its second position to thus effect said retention of said control member in its second position and said movement of said fluid flow control member to its flow-permitting position.

5. In a control device, a magnet member biased to a first position, an armature for said magnet member biased away from said magnet member to a first position and movable against said bias to a second position, a fluid flow control member fixed to said armature and being in flow-preventing position when said armature is in its first position and in flow-permitting position when said armature is in its second position, said magnet member being movable against its bias to a second position engaging said armature, a shaft rotatable between first and second positions, a control member operatively associated with said shaft and movable between first and second

controlling positions by rotation of said shaft between its first and second positions, cooperating abutment means on said magnet member and said shaft operable to rotate said shaft and to dispose said control member in its second position on movement of said magnet member to its second position, such movement of said magnet member to its second position maintaining said fluid flow control member in its flow-preventing position, abutment means on said armature cooperating with the abutment means on said shaft and operable to retain said shaft and said control member in their said second positions on movement of said armature to its said second position, such movement of said armature to its second position moving said fluid flow control member from its flow-preventing position to its flow-permitting position, and thermoresponsive coupling means for said magnet member and armature operable during existence of a given condition when said magnet member is moved against its bias to its second position in engagement with said armature to couple said magnet member and armature, whereby the bias of said magnet member, on release of said magnet member when coupled to said armature effects return of said magnet member to its first position and movement of the coupled armature therewith to its second position to thus effect said retention of said control member in its second position and said movement of said fluid flow control member to its flow-permitting position.

6. In a control device, an assembly comprising first and second movable members having relative attracted and separated positions, coupling means to retain said members in relative attracted position when moved thereto, means for effecting movement of said first member from an initial position separated from said second member to an attracted position relative to said second member, means for returning said first member to its initial position while said second member is coupled therewith, control means actuatable from a first controlling position to a second controlling position, rotatably operable actuating means for control means, and first and second connecting means movable with said first and second members respectively coacting with said actuating means, movement of said first member from its said initial position to its said attracted position through its said connecting means effecting rotation of said actuating means a given amount for actuation of said control means from its first to its second controlling position, said second member through its said connecting means maintaining said actuating means in the position to which it is rotated by said first member movement and thereby maintaining said control means in its second controlling position upon return of said first member to its initial position while said members are coupled.

7. In a control device, an assembly comprising first and second movable members having relative attracted and separated positions, coupling means to retain said members in relative attracted position when moved thereto, means for effecting movement of said first member from an initial position separated from said second member to an attracted position relative to said second member, means for returning said first member to its initial position while said second member is coupled therewith, control means actuatable from a first controlling position to a second controlling position, rotatably operable actuating means for said control means, and means movable with said members respectively cooperating with said actuating means to effect rotation of said actuating means a given amount for actuation of said control means from its first to its second controlling positions with movement of said first member from its initial position to said attracted position and to maintain said actuating means in the position to which it is rotated by said first member movement and thereby to maintain said control means in its second controlling position upon return of said first member to its initial position with movement of said

second member to a second position when said members are coupled, release of said coupling means permitting return of said second member to its initial position, reverse rotation of said actuating means and return of said control means to its first controlling position.

8. In a control device, an assembly comprising first and second magnetically permeable members having relative attracted and separated relation, reset means operable when said members are in separated relation for moving said first member from a first position toward a second position and into attracted relation with said second member, coupling means operable to hold said first and second members in attracted relation, means for returning said first member to its initial position, control means operable to move between a first controlling position and a second controlling position, means including a rotatable member for moving said control means between its controlling positions, and connection means

between said rotatable member and said magnetic members operable upon movement of said first member from its first position to its said second position to rotate said rotatable member and thereby actuate said control means

5 toward its second controlling position, said connection means upon coupling of said other member to said one member being operable to maintain said rotatable member in the position to which it is rotated by said first member movement and thereby to maintain said control means in its said second controlling position.
